CLAIM

The ornamental design for a display fixture for highlighting products, as shown and described.

DESCRIPTION

FIG. 1 is a perspective view of a display fixture for highlighting products in accordance with the present disclosure.

FIG. 2 is an enlarged perspective view of a corner of a display fixture for highlighting products in accordance with the present disclosure.

FIG. 3 is a front elevational view of a corner of a display fixture for highlighting products in accordance with the present disclosure.

FIG. 4 is a rear elevational view of a corner of a display fixture for highlighting products in accordance with the present disclosure.

FIG. 5 is a top plan view of a corner of a display fixture for highlighting products in accordance with the present disclosure; and,

FIG. 6 is a side elevational view of a corner of a display fixture for highlighting products in accordance with the present disclosure.

The broken lines shown as dash-dot-dot lines are for the purposes of illustrating the environment in which the article resides and form no part of the claimed design. The broken away symbols shown as dashed lines in the drawings indicate the appearance of any portion of the article between the break lines forms no part of the claimed design.

1 Claim, 5 Drawing Sheets
